CLAIM

The ornamental design for a multipurpose laundry cart, as shown and described.

DESCRIPTION

FIG. 1 is a front top perspective view of a laundry cart showing of my new design;

FIG. 2 is a front top perspective view thereof without the baskets;

FIG. 3 is a front bottom perspective view thereof;

FIG. 4 is a front bottom perspective view thereof without the baskets;

FIG. 5 is a rear top perspective view thereof;

FIG. 6 is a rear top perspective view thereof without the baskets;

FIG. 7 is a top plan view thereof;

FIG. 8 is a bottom plan view thereof;

FIG. 9 is a left-side elevational view thereof;

FIG. 10 is a right-side elevational view thereof;

FIG. 11 is a front elevational view thereof; and,

FIG. 12 is a rear elevational view thereof.

The broken line showing of the wheels, the axle, and the baskets are included for the purpose of illustrating environmental structure and forms no part of the claimed design.
